US0D1056187S

(12) United States Design Patent (10) Patent No.: US D1,056,187 S
(45) Date of Patent: * Dec. 31, 2024

(54) DIFFUSER FOR PERFUMES OR ESSENTIAL OILS

(71) Applicant: GREEN ESTELLE Co., Ltd.,
Jeollanam-do (KR)

(72) Inventor: Boin Chung, Gwangju (KR)

(73) Assignee: GREEN ESTELLE CO., LTD.,
Jangseong-Gun (KR)

() Term: 15 Years

(21) Appl. No.: 35/519,757

(22) Filed: Oct. 11, 2023

(80) Hague Agreement Data

Int. Filing Date: Oct. 11, 2023

Int. Reg. No.: DM/234462

Int. Reg. Date: Oct. 11, 2023

Int. Reg. Pub. Date: Jan. 26, 2024
